(57) **CLAIM**

The ornamental design for a surface configuration of a front panel for a vehicle, as shown and described.

DESCRIPTION

FIG. 1 is a front view of a surface configuration of a front panel for a vehicle according to my novel design;

FIG. 2 is a right side view of a surface configuration of a front panel for a vehicle according to my novel design, the left side view being mirror symmetrical;

FIG. 3 is a top view of a surface configuration of a front panel for a vehicle according to my novel design;

FIG. 4 is a bottom view of a surface configuration of a front panel for a vehicle according to my novel design; and,

FIG. 5 is a perspective view from the front left of a surface configuration of a front panel for a vehicle according to my novel design.

The broken line included depicts environment and is not part of the claimed design.
